Des. 214,290
Patented May 27, 1969

214,290

DESK MODEL TELEVISION RECEIVER OR THE LIKE

Karl A. Miklas, Park Ridge, Ill., assignor to Warwick
Electronics Inc., Chicago, Ill., a corporation of
Delaware

Filed June 12, 1968, Ser. No. 12,309

Term of patent 14 years

Int. Cl. D14—03

U.S. Cl. D56—4

FIGURE 1 is a perspective view of a desk model television receiver embodying the design of this invention; FIGURE 2 is a front elevational view thereof;

FIGURE 3 is a top plan view thereof;

FIGURE 4 is a side elevational view thereof, the other side being substantially a mirror image;

FIGURE 5 is a rear elevational view thereof; and

FIGURE 6 is a perspective view thereof showing the viewing portion of the television receiver rotationally displaced from the position shown in the other figures.

The dominant features of the design are shown in full lines on the drawings.

I claim:

The ornamental design for a desk model television receiver or the like, as shown and described.
